PAUL ACKERMAN, OF TORONTO, ONTARIO, CANADA, ASSIGNOR, BY MESNE ASSIGNMENTS, TO GENERAL ELECTRIC COMPANY, A CORPORATION OF NEW YORK.

SELECTIVE CUT-OUT FOR ALTERNATING-CURRENT CIRCUITS.

1,192,724.

Specification of Letters Patent. Patented July 25, 1916.

Application filed October 17, 1912. Serial No. 726,202.

To all whom it may concern:

Be it known that I, PAUL ACKERMAN, of the city of Toronto, in the county of York, in the Province of Ontario, Canada, have invented certain new and useful Improvements in Selective Cut-Outs for Alternating-Current Circuits, of which the following is the specification.

My invention relates to improvements in selective cut-outs for alternating current circuits and the object of the invention is to provide a reliable and positive means for automatically preventing a reverse energy flow in the faulty feeder or transmission line of a system of distribution comprising a number of feeders or transmission lines in parallel. To this end, I provide for each transmission line two or more differentially wound relays each having one coil energized by current derived from the line to be protected and the other coil energized by current derived from another one of the transmission lines, and so connected that when all of the coils act conjointly to operate the relays the automatic circuit breaker will be tripped to open the circuit through the transmission line. The relays act conjointly when a fault develops of such a character that there is a reversal of energy flow through the transmission line and consequently through the coils of the relays, all the relays connected to the line act conjointly and trip the circuit breaker. The faulty transmission line or feeder is automatically selected and cut off from the system as soon as the direction of energy flow in the line reverses.

The drawing represents a diagrammatic view of my apparatus showing the various circuits, switches and operating means for a single phase system of parallel feed wires with the automatic reverse current cut out provided for every one of the feed wires.

In the drawings like letters of reference indicate corresponding parts in each figure.

A¹, A² and A³ are a series of alternating generators connected in parallel by transmission lines or feeders.

A⁴ and A⁵ are feed wires extending from the generator A¹.

A⁶ and A⁷ are feed wires extending from the generator A².

A⁸ and A⁹ are feed wires extending from the generator A³.

B¹ and B² are the primary coils of a

current transformer located in the feed wires A⁴, A⁶ and A⁸ respectively.

C and C¹ are bus wires, the feed wires A⁴, A⁶ and A⁸ leading to the bus wire C and the feed wires A⁵, A⁷ and A⁹ leading to the bus wire C¹.

In the transmission line or feeder there is an automatic circuit breaker. In the particular form shown D¹ and D² are circuit breaker contacts located in the feed wire A⁴. 65

D² and D³ are circuit breaker contacts located in the feed wire A⁶, and D⁴ and D⁵ are circuit breaker contacts located in the feed wire A⁸.

E is a movable bridging contact connecting the contacts D¹ and D². 70

E¹ is a movable bridging contact connecting the contacts D² and D³.

E² is a movable bridging contact connecting the contacts D⁴ and D⁵. 75

It will be understood that the movable bridging contacts E, E¹ and E² are normally, as shown in the drawing, in position to keep the circuit closed.

F is a battery. 80

F¹ and F² are wires leading from the battery terminals.

F³, F⁴ and F⁵ are branch battery circuits extending from the wires F¹ and F² in proximity to each of the feed wires A⁴, A⁶ and A⁸. 85

F⁶ is an operating or trip coil located in the branch battery circuit F³ and designed to open when energized the circuit breaker E.

F⁷ and F⁸ are similar trip coils for controlling the circuit breakers E¹, E². 90

The branch circuit F³ is provided with a pair of switch contacts 2 and 3, and a pair of switch contacts 4 and 5. The branch circuit F⁴ is provided with a pair of switch contacts 6 and 7 and a pair of switch contacts 7¹ and 8, and the branch circuit F⁵ is provided with a pair of switch contacts 9 and 10 and a pair of switch contacts 11 and 12. These contacts are normally open so as to break the respective branch battery circuit. 95

13 is a closing contact designed to bridge the contacts 2 and 3.

14 is a closing contact designed to bridge the contacts 4 and 5.

15 is a closing contact designed to bridge the contacts 6 and 7. 105

16 is a closing contact designed to bridge the contacts 7¹ and 8.

17 is a closing contact designed to bridge the contacts 9 and 10, and 18 is a closing 110

contact designed to bridge the contacts 11 and 12.

Each closing contact 13, 14, 15, 16, 17, and 18 is provided with a movable operating solenoid core 19.

H, H¹ and H² are the secondary coils of a current transformer located in the feed wires A⁴, A⁶ and A⁸.

H²¹ is an upper current coil surrounding the solenoid core 19 of the closing contact 13.

H²² is a current coil surrounding the solenoid core 19 of the closing contact 14.

H³¹ is a lower current coil surrounding the solenoid core 19 of the closing contact 15 and H⁴ is a lower current coil surrounding the solenoid core 19 of the closing contact 18.

H⁵ is a circuit wire leading from the secondary coil H of the current transformer through the coil H²¹, coil H²², coil H³¹ and coil H⁴ back to the other terminal of the secondary coil H.

H⁶ is an upper current coil surrounding the solenoid core 19 of the closing contact 15.

H⁷ is a current coil surrounding the solenoid core 19 of the closing contact 16.

H⁸ is a lower current coil surrounding the solenoid core 19 of the closing contact 17 and H⁹ is a current coil surrounding the solenoid core 19 of the closing contact 13.

H¹⁰ is a circuit wire leading from one terminal of the secondary coil H¹ of the current transformer located in the feed wire A⁶. This circuit extends through the coil H⁶, coil H⁷, coil H⁸, coil H⁹ back to the other terminal of the secondary coil H¹.

H¹¹ is an upper current coil surrounding the solenoid core 19 of the closing contact 17.

H¹² is an upper current coil surrounding the solenoid core 19 of the closing contact 18.

H¹³ is a lower current coil surrounding the solenoid core 19 of the closing contact 15.

H¹⁴ is a current coil surrounding the solenoid core 19 of the closing contact 14.

H¹⁵ is a wire leading from the secondary coil H² through the current coils H¹¹, H¹², H¹³, and H¹⁴ back to the other terminal of the secondary coil H².

I and I¹ are wires leading from the bus wires C and C¹ to a distributing system.

Having described the principal parts involved in my invention I will briefly describe the operation of the same. The current in the feed wires A⁴, A⁶ and A⁸ is assumed to flow in the direction of arrow from the alternating current generators A¹, A² and A³. For the sake of illustration a short circuit is assumed to occur at the point indicated by dotted line 16 connecting the feed wires A⁴ and A⁵ making necessary to open the circuit breaker to maintain a normal condition in the distributing system. It

will be readily understood that such a short circuit will result in a momentary current passing through the feed wire A⁴ and primary coil B in a reverse direction to the normal flow. This will induce a similar current in the secondary coil H. It will also be understood that the two coils of each relay are differentially wound, so that the normal flow of current through each of the upper current coils H², H²¹, H⁶, H⁷, H¹¹ and H¹² is in an opposite direction to the lower current coils H², H¹⁴, H¹³, H³¹ and H⁴ and H⁸, thereby holding the closing contacts 13, 14, 15, 16, 17 and 18 in the open position. As soon as the current flow is reversed in one of the feed wires, the current in the secondary coil of the corresponding current transformer will reverse also, thus reversing the current in all current coils in series with that secondary coil. For instance, as above described, the current in the feed wire A⁴ is reversed by a short circuit, the current in the coils H²¹, H²², H³¹, H⁴ will then reverse and therefore close the corresponding contacts 2, 3, 4 and 5, and 7¹, 8, 11 and 12. This has the effect of closing the branch battery circuit F³ and opening the circuit breaker E of the faulty feed wire by the coil F⁶. At the same time the other two circuit breakers of the two remaining feed wires are left closed to maintain an uninterrupted service over the wires I, I¹, to the distributing system. It will be readily understood that a similar result will occur should the short circuit occur between the feed wire A⁶ and A⁷ or A⁸ and A⁹ cutting out the faulty feed wire.

I am aware that the battery circuit closure has been in use before for operating the circuit breaker, such closure having solenoids with two current coils making contacts by lifting a solenoid core upon reversal of the current in one element or a torque developing instrument consisting of two current elements making contact upon reversal of current in one of the elements to change the direction of movement of the revolving part. But in both these devices for the battery circuit one current element was fed from a current transformer while the other element was fed from a potential transformer. It will be readily understood that such a device is most unreliable for the reason that the current in the potential coil may drop to a zero point under complete short circuit conditions, and would, therefore, fail to operate the closure instantaneously at a low reversal current.

In my device all current coils operating the closures of the battery currents are fed from current transformers and will, therefore, operate the closure instantaneously and under all circumstances.

It will be understood that any other source of electromotive force could be used

instead of the battery for actuating the release coil of the circuit breaker.

It is further understood that the device shown can be used for any alternating system of multiple phases in applying the same arrangement properly for corresponding phases of parallel feeders.

It is further understood that the same device can be applied to any additional parallel feeder in making a similar combination of the feeder with any two parallel feeders.

It is further understood that for operation of the switches of the battery circuit any device could be applied which is operated by two current elements and which will close the switch upon reversal of the current in one of the current elements. And finally it will be understood that my device is only operated by a reverse current flow and not by a straight overload.

From this description it will be seen that I have devised a very simple device whereby a circuit breaker is operated when a short circuit and consequent reverse current occurs in the feed wire, by utilizing only the currents of current transformers, making its operating positive and reliable at all times and under all circumstances.

Thus it will be seen that the tripping of any circuit breaker is dependent on the operation of two sections of a composite relay each portion of which is supplied by series transformers controlled by different feeders, and that the circuit will not be opened except by the conjoint operation of the two sections one coil system of which is supplied by one feeder and the other by another feeder of the system.

What I claim as my invention is—

1. Means for opening a defective feeder of an alternating current supply system upon reversal of energy flow, comprising a plurality of series transformers, in different feeders, each having its primary winding in series with its feeder, a pair of relays and a circuit-breaker for each feeder, each relay having differential coils one of which is supplied by the secondary of the transformer of the feeder which it governs, and the other by different transformers of the other feeders, and a tripping circuit including both of the relay contacts and trip coil of the circuit-breaker, whereby upon a fault in any feeder its circuit will be opened.

2. In a system of distribution comprising transmission lines in parallel and means in each line for deriving a current from said line, means for opening a defective line comprising an automatic circuit breaker and tripping mechanism for said circuit breaker comprising two pairs of differential coils, one coil of each pair being energized by current derived from the defective line, and the other coil of each pair being energized by

current derived from another transmission line.

3. In a system of distribution for alternating currents, means for selectively opening any defective circuit of a group, comprising two relays for each circuit having independently movable armatures, a circuit-breaker for each circuit, means co-operating with said relay armatures to cause conjoint action of said armatures to trip the circuit breaker, a pair of differential coils for each relay armature, and a series transformer in each circuit of the group supplying current to one coil of each of its own relays and to one coil only of each pair corresponding to the other circuits of the group.

4. In a system of distribution for alternating currents, means for selectively opening any defective circuit of a group, comprising a circuit-breaker, two differential relays for each circuit, two contacts in series controlled by the relay armatures, a source of trip current adapted to operate any trip coil when both contacts are closed, and a series transformer in each circuit supplying a coil of each of the relays controlling the circuit in which it is interposed and a coil of a relay of another circuit.

5. In a reverse current operated cut out, the combination with a series of feed wires leading from a suitable current supply, of a circuit breaker located in one feed wire, a suitably energized circuit breaker operating means and a circuit leading therethrough, a pair of open switches having contacts located in the circuit breaker operating circuit in series with the circuit breaker operating means, a current transformer comprising a primary coil located in one feed wire and a secondary coil, a pair of electro-magnetic operating means for each switch closure one means of each pair being energized from the secondary transformer coil of one feed wire, the other means of one pair being energized from the second feed wire of the series and the other means of the other pair being energized from the third feed wire of the series whereby one means of each pair normally neutralizes the other means to hold the switches open and whereby each pair of means co-operate together to simultaneously close the switches upon the current being reversed in one means of each pair by the reversal of the current in the first feed wire thereby closing circuit breaker operating circuit and opening current breaker, and independently close the switch closures by the reversal of the current in the other means of either pair by the reversal of the current in the second or third feed wires whereby the circuit breaker operating means is kept open and the circuit breaker closed, as and for the purpose specified.

6. In a system of distribution for alternating currents, a plurality of feeders, a

series transformer and a circuit breaker for each feeder, a pair of relays for tripping each circuit breaker, means for connecting the relay contacts associated with each circuit breaker so that conjoint action of the relay armatures will actuate the trip coil of the circuit breaker, and a pair of differential coils on each relay, one coil of each pair being derived from the series transformer of one feeder and the other from the transformer of another feeder.

7. The combination with a plurality of parallel transmission lines of a plurality of differential relays for each line, each relay having an armature and two opposing wind-

ings for actuating said armature, one winding of each relay being responsive to current in the line and connected in series with the corresponding winding of the other relays for said line, and the other winding of each relay being responsive to current in a different one of said transmission lines, a circuit breaker in each line and means for causing the conjoint action of the armatures of the relays for said line to trip said circuit breaker.

PAUL ACKERMAN.
